(57) **CLAIM**

The ornamental design for LED lamp unit, as shown and described.

DESCRIPTION

FIG. 1 is a front elevational view of a LED lamp unit showing my new design;

FIG. 2 is a rear elevational view thereof;

FIG. 3 is a left side view thereof;

FIG. 4 is a right side view thereof;

FIG. 5 is a top plan view thereof; and,

FIG. 6 is a bottom plan view thereof.

The broken line showing of the bottom surface in FIG. 6 is to show environmental structure only and forms no part of the claimed design.
